(57) **CLAIM**

The ornamental design for a control box, as shown and described.

DESCRIPTION

FIG. 1 is a perspective view of a control box showing my new design;

FIG. 2 is a bottom plan view thereof;

FIG. 3 is a top plan view thereof;

FIG. 4 is a right side elevational view thereof;

FIG. 5 is a left side elevational view thereof;

FIG. 6 is a front elevational view thereof; and

FIG. 7 is a rear elevational view thereof;

FIG. 8 is a perspective view of a second embodiment of a control box showing my new design;

FIG. 9 is a bottom plan view thereof;

FIG. 10 is a top plan view thereof;

FIG. 11 is a right side elevational view thereof;

FIG. 12 is a left side elevational view thereof;

FIG. 13 is a front elevational view thereof; and,

FIG. 14 is a rear elevational view thereof.

(Continued)

The broken lines illustrate portions of the control box which form no part of the claimed design.
